RACING GAME APPARATUS

Alfred German Rose, Gainsborough, and Kenneth Howard Nicholls, Bromley, England

Application December 4, 1948, Serial No. 63,572

9 Claims. (Cl. 273—86)

1

This invention relates to toy figures that are capable of unaided progression by a rocking motion, when placed on an inclined plane as described, for example, in United States Patent No. 2,601,739.

According to the invention, there is provided the combination with a figure of the above kind of an inclined track provided with a controlling surface adapted to be engaged by a projection on a limb member of said figure during rocking motion thereof so as to interfere with the free oscillation of the figure during progression, and means for varying the height of the controlling surface relatively to the track so as to vary the periodicity of the oscillation of said figure. By these means, therefore, the time taken for the figure to travel along the track can be varied in accordance with the setting of the controlling surface.

A plurality of tracks, each provided with a controlling surface and each accommodating a figure may be arranged as a single structure so as to constitute a racing game, and in such a case, the controlling surfaces may be connected to a single varying means which may be arranged to vary the height of the individual surfaces by differing amounts.

The controlling surface may be constituted by the surface of a rotatable shaft formed with one or more longitudinal flats or depressions the shaft running lengthwise of the track and arranged below the track, a longitudinal slot being formed in the track for the passage of the projection on the figure. The flats may vary as to length and relative position so that at any setting of the shaft a surface varying in height along its length is presented to the projection on the figure. The shaft may be provided at one end with a hand knob for turning purposes, and where a plurality of tracks are used as described above, the shafts may be connected by gearing or bands of any desired ratio in which case one turning knob only would be required. The controlling surface or surfaces may be provided with a covering of rubber or like friction material. Alternatively, the controlling surface may be molded from plaster or like material.

Instead of the rotatable shaft described above, the controlling surface may take the form of a web running lengthwise of the track and formed with protuberances or depressions serving to vary the height of the surface relatively to the track, the web being movable longitudinally to vary the positions of the protuberances or depressions.

2

When used as a racing game, it is preferable that the surfaces presented to the projections on the figures should not be visible to the competitors, and for this reason, the projections on the figures are preferably of a thin blade-like nature and the slots in the tracks are very narrow, the surfaces being enclosed in the track-supporting structure. With such construction, the slots in the tracks may serve also to guide the figures.

The projection may also be made variable in effective length so as to provide an additional means for varying the periodicity of the oscillation of the figure.

When figures in the form of horses and riders as described in the specification mentioned above are used in conjunction with a plurality of tracks as described above, the invention provides a particularly attractive and fascinating horse-racing game having very realistic effects.

The invention will now be described in greater detail with reference to the accompanying drawings, as applied to such a game.

In the drawings:

Figures 1, 2 and 3 are a sectional elevation, plan and sectional end view, respectively, of a horse-racing game according to the invention.

Figures 4 to 7 are sectional views illustrating the shape of the controlling surfaces, and

Figures 8 and 9 are a sectional elevation and plan view, respectively, of the same game as shown in Figures 1 to 3 having a modified form of controlling surfaces.

Referring to Figures 1 to 3, a series of toy horses 11, are arranged for progression by a rocking motion down an inclined track 12 formed with a series of narrow slots 13 for the passage of blade-like projections 14 on the horses 11.

The horses 11 are provided with a fixed limb member 41 on which the fore legs are formed and a freely mounted limb member 42 on which the hind legs are formed, the member 42 being pivoted at 43 in the body portion of the horse

11. When the figures are placed on the tracks 12, therefore, and given a slight rocking motion, they progress down the track by rocking alternately on the limb members 41 and 42; the limb member 42 swinging forwardly as the figure rocks forwardly on the limb member 41, while the limb member 41 swings forwardly as the figure rocks rearwardly on the limb member 42.

The track 12 is supported on end frames 16 and 17 in which is rotatably mounted a series of rotatable shafts 18 which are identical in construction and arranged one below each slot 13.

The shafts 18 are each formed with a series of flats 19 varying in length and position so that, whatever the circumferential position of the shaft 18, it presents a controlling surface to the adjacent projection 14 that varies in height along its length. The shafts 18 are provided with pulleys 21 of different diameters round which a rubber driving belt 22 is threaded in the manner shown in Figure 3, the belt 22 also passing over a driving pulley 23, rotatably mounted in the supporting frame 16 and an auxiliary bearing member 24, and also over a guiding pulley 26. The driving pulley 23 is provided with a crank 27 for the purpose of rotating the four shafts 18 simultaneously.

The construction of the shafts 18 is illustrated by Figures 4 to 7 which are sectional views taken at different positions along the length of a shaft, and will be seen that upon turning the crank 27, the shafts 18 will be rotated to different degrees and will each present a different surface to the projections 14 of the corresponding horse 11. During rocking motion of the horses 11 as they progress down the track 12, therefore, the projections 14 will engage the different surfaces presented by the shafts 18 which will thus interfere to varying degrees with the free oscillation of the horses 11, and as each surface varies in height along its length, the periodicity of the oscillation is varied at different intervals along the length of the track. A slight turning of the crank 27 is sufficient to vary to different degrees the surfaces presented to the projections 14 of the horses 11 thus making it extremely difficult to predict which horse will reach the end of the track first. The horses 11 are started simultaneously by means of a spring-loaded starting lever 28 which is arranged to engage the rear limbs of the horses as illustrated in Figure 1.

In Figures 8 and 9 the general construction of the track is the same as that shown in Figures 1 to 3, but the controlling surfaces in this case are formed on endless bands 31 arranged on supporting pulleys 32 and 33 rotatably mounted in the framework 34 supporting the track 12. The pulleys 33 are of different diameter and are formed on a common shaft provided with a crank 36 for the purpose of rotating the pulleys. The bands 31 are of molded rubber and are formed with protruberances 37 of different length spaced at different intervals along the length of the bands for the purpose of varying the height of the surfaces presented to the projections 14 of the horses 11. It will be seen that upon rotation of the crank 36 the bands 31 are moved lengthwise of the track to different degrees thereby altering the position of the protruberances 37 so as to vary the times at which they will engage the projections 14 for the purpose of varying the periodicity of the oscillation of the horses 11.

We claim:

1. A toy of the kind in which a figure progresses unaided by rocking alternately on two limb members, said toy comprising an inclined track, a figure having a body portion formed with a fixed limb member and a freely mounted limb member pivotally attached to the body portion, the freely mounted limb member and the body portion swinging forwardly alternately as the figure rocks on the track on the two limb members, a movable controlling surface disposed below and lengthwise of the track and formed with portions of different height, a thin blade-like projection extending from one of the limb members, the track being formed with a very narrow

slot for the passage of the projection through the track so as to allow the projection periodically to engage the controlling surface during rocking motion of the figure and thus interfere with the free oscillation of the figure during progression, and a controlling member for moving said surface to bring portions of different height into operative position so that as the projection engages the portions of different height the periodicity of the oscillation of the figure is varied.

2. A toy as in claim 1, wherein the controlling surface is constituted by the surface of a rotatable shaft running lengthwise of the track.

3. A toy as in claim 2, wherein the portions of different height vary as to length and relative position so that at any setting of the shaft a surface varying in height along its length is presented to the projection.

4. A toy of the kind in which figures each progress unaided by rocking alternately on two limb members, comprising a plurality of inclined tracks, a plurality of figures, there being one of said figures for each of said tracks, controlling surfaces disposed below and lengthwise of said tracks respectively, a shaft mounting each controlling surface for rotation on an axis extending lengthwise with respect to its track, each of said figures having a body portion with a fixed limb member and a pivoted limb member, said pivoted limb member and the body portion swinging forwardly alternately as the figure rocks on the track on the two limb members, a thin blade-like projection extending from one of the limb members, each track having a narrow slot for the passage of said projection through the track so as to allow the projection periodically to engage the related controlling surface during rocking motion of the figure and thus interfere with the free oscillation of the figure during progression, each of said controlling surfaces embodying portions of different height which vary as to length and relative position so that at any setting of said shaft a surface is presented to said projection for the aforesaid purpose, and a common controlling member for moving the respective shafts of said controlling surfaces.

5. A toy as in claim 4, comprising a common retaining member for holding the several figures against movement on the tracks, release of said member effecting simultaneous starting of the progression of the figures on the tracks.

6. A toy of the kind in which a figure progresses unaided by rocking alternately on two limb members, said toy comprising an inclined track, a figure having a body portion formed with a fixed limb member and a freely mounted limb member pivotally attached to the body portion, the freely mounted limb member and the body portion swinging forwardly alternately as the figure rocks on the track on the two limb members, a movable controlling surface disposed below and lengthwise of the track and formed with portions of different height, the controlling surface being constituted by a web running lengthwise of the track, a thin blade-like projection extending from one of the limb members, the track being formed with a very narrow slot for the passage of the projection through the track so as to allow the projection periodically to engage the controlling surface during rocking motion of the figure and thus interfere with the free oscillation of the figure during progression, and a controlling member for moving said surface in the lengthwise direction of the track to vary the position

of the portions of different height so that the projection may be caused to engage those portions at different times to vary the periodicity of the oscillation of the figure.

7. A toy as in claim 6, wherein the web is in the form of an endless band, and pulleys which support the band.

8. A toy of the kind in which figures each progress unaided by rocking alternately on two limb members comprising a plurality of inclined tracks, a plurality of figures, there being one of said figures for each of said tracks, movable controlling surfaces disposed below said tracks respectively, each controlling surface having portions of different height and constituted by a web running lengthwise of the related track, each of said figures having a body portion with a fixed limb member and a pivoted limb member, said pivoted limb member and the body portion swinging forwardly alternately as the figure rocks on the track on the two limb members, a thin blade-like projection extending from one of the limb members, each track having a narrow slot for the passage of said projection through the track so as to allow the projection periodically to engage the related controlling surface during rocking motion of the figure and thus interfere with the free oscillation of the figure during progression, each of said controlling surfaces embodying portions of different height which vary as to length and relative po-

sition so that the projection may be caused to engage those portions at different times to vary the periodicity of the oscillation of the figure, and a common controlling member for moving said surfaces simultaneously.

9. A toy as in claim 8, wherein the common controlling member comprises a series of driving pulleys, one for each band, secured to a common controlling shaft, the driving pulleys being of different diameter.
